FREDERICK PHILLIPS, OF BRIXTON, LONDON, ENGLAND, ASSIGNOR TO THE NATIONAL CASH REGISTER COMPANY, OF DAYTON, OHIO, A CORPORATION OF OHIO.

MACHINE FOR PRINTING AND ISSUING TICKETS AND THE LIKE.

1,425,050.

Specification of Letters Patent. Patented Aug. 8, 1922.

Application filed April 26, 1919, Serial No. 292,901. Renewed January 7, 1921. Serial No. 435,758.

To all whom it may concern:

Be it known that I, FREDERICK PHILLIPS, a subject of the King of Great Britain, residing at 16, Bonham Road, Brixton, in the county of London, England, have invented 5. certain new and useful Improvements in or Relating to Machines for Printing and Issuing Tickets and the like, of which the following is a specification.

10. The present invention relates to machines for printing and issuing tickets and the like (hereinafter referred to as tickets), of the kind in which a number of strips from which the tickets are made are printed on one or 15. both sides and suitably severed to form printed tickets which tickets are issued from the machine by its action. The printed tickets so produced and issued usually have to be respectively of different price or other 20. like denomination or special character, and it is very desirable in many cases, as for instance in the case of tickets for places of amusement and canteens, that the paper or other material from which the tickets are 25. made shall be of a different colour or basic character for each denomination in order to facilitate identification but with the present knowledge it is only feasible to provide for this in machines of the said kind by employing 30. for each strip a special set of devices for dealing with the strip to complete and form the ticket after or before its special denominational character has been given to it, such devices being, for instance, numbering 35. and dating means, rouletting or perforating means (in the case of a ticket comprising a part, usually termed a "stub" which has to be separated from the body of the ticket after its issue), and a severing knife 40. and ejecting means. Therefore machines for the purpose described, by which the tickets have to be made from several different strips of material, are of comparatively objectionable size and have a very large number of 45. parts rendering them costly to produce and maintain and the main object of the present invention is to simplify such machines and reduce their bulk.

According to the said invention only a 50. single set of dating and numbering means, the rouletting or perforating means, the severing knife and other devices of general use with a number of strips in the production of all the tickets in common is provided for a 55. plurality of sets of devices for giving to the

tickets to be made respectively from the various strips their special denominations or characters, and the said single set of general devices is so arranged with respect to the means for giving the special denominations 60 as aforesaid to the tickets that the position of the last mentioned means relatively to the devices of general use may be changed at will from time to time so that the one set of the said devices of general use may be caused 65 to operate on any one of the several ticket strips according as desired.

In a convenient embodiment of the said invention a plurality of strips are led to the operative parts of the machine through 70 guides arranged on a member of approximately sector shape (hereinafter referred to as the strip carrier) capable of turning on an axis at the part where the radii of the sector meet the said guides being disposed in the form a radii at equal distances apart and terminating in slot apertures in the arcuate surface of the said carrier. Beneath the said arcuate surface and suitably arranged on each side of each strip glide is a printing 80 roller for printing a denomination or the like on the strip and co-acting therewith an impression roller and inking roller, the co-operation of the printing and impression rollers for each strip causing the strip to be 85 fed through the slot for it in the arcuate surface of the strip carrier. The strips enter their guides in the said carrier at a part approximately coincident with the axis on which it turns and where the several guides 90 almost meet. Secured in the machine in juxtaposition to the arcuate surface of the strip carrier is a set of devices for rouletting or perforating dating and numbering, and severing and issuing each ticket in succession 95 from the machine irrespectively of the particular strip from which it has been produced, and means are provided such as a hand lever with connections with a shaft on the strip carrier at its axis by which the said carrier may be moved into any one of several 100 positions corresponding in number to the number of strips capable of being dealt with so that any one of the several slots from which the several strips of material issue from the strip carrier may be brought into proper position in relation to the devices of general use to cause the strip after having received its denominational printing or the like to pass 105 through and be operated on by the devices of 110

- general use, that is, the rouletting or perforating means, the numbering and dating means, and the severing and issuing means. The aforesaid strip carrier is suitably counterbalanced and spring detent devices are provided to cause it to stop in any one of its proper positions and to retain it there against slight hand pressure on its operating lever.
- 10 The said invention comprises other novel features as will hereinafter appear.
- In order that the said invention may be clearly understood and readily put in practice, it is hereinafter particularly described 15 with reference to the accompanying drawings which illustrate by way of example the preferred embodiment thereof.
- Figure 1 is a side view of the machine.
- Figure 2 is a plan thereof, and
- 20 Figure 3 is a side view of the left hand side of Figure 1. In these figures the inking ribbon for the numbering and dating wheels is omitted for the sake of clearness.
- Figures 4 to 38 illustrate separately various sections of the mechanism of the machine and members thereof, all these figures being somewhat diagrammatic. Of these figures, Figure 4 is a front view of the main member of which the strip carrier is composed, and Figure 5 is a rear view of the same. Figure 6 is an edge view of the said member, and Figure 7 is a plan view thereof. Figure 8 is a face view of a plate which is connected to that illustrated in Figures 35 4 and 5 and forms part of the strip carrier. Figure 9 is a face view of one of the guide members for the strips of material which forms part of the strip carrier, and Figure 10 is an edge view of the same showing 40 mounted thereon one of the inking rollers of the denominational printing mechanism. Figure 11 is a face view of one of the guide members which co-acts with that illustrated in Figures 9 and 10 showing mounted 45 thereon the locking device for the impression roller of the denominational printing mechanism which is carried by the said guide member, and Figure 12 is an edge view of the guide member illustrated in Figure 11. Figure 13 is a face view of one of the impression rollers aforesaid and its carrier bracket, and Figure 14 is an end view of the same. Figure 15 is a side view of one of the printing rollers of the denominational printing mechanism, and Figures 16 50 and 17 are end views thereof. Figure 18 is a face view and end view of one of the locking devices for the printing rollers. Figure 19 is a view of one of the inking rollers aforesaid and Figure 20 is an inner face view of the upper part of the guide illustrated in Figures 9 and 10. Figure 21 is a face view of the means for operating the strip carrier and locking the main mechanism while it is being operated. Figure 22

is a face view from the rear of the means by which the counters for the tickets of each denomination are operated. Figure 23 is a face view of the means by which motion is given to the main mechanism. Figure 24 is 70 a face view showing the gearing by the medium of which the denominational printing is effected. Figure 25 is a diagrammatic side view of the machine similar to Figure 3, but illustrating the clutch mechanism 75 used in effecting the denominational printing and some of the mechanism for holding the strip on the platen while it is being rouletted or perforated. Figure 26 is a side view of the driving shaft operating the 80 clutch aforesaid, and a side view and end view of the clutch member. Figure 27 is a side view of the mechanism for operating the said clutch, and Figure 28 is a plan of part thereof. Figure 29 is a side view of 85 the mechanism for operating the rouletting or perforating wheel. Figure 30 is a side view of the said rouletting wheel and its carrier. Figure 31 is a side view of the mechanism for holding the strip on the 90 platen while it is being rouletted or perforated. Figure 32 is a plan view of the said mechanism. Figure 33 is a plan view illustrating the mechanism for operating the rouletting or perforating wheel, and the 95 relative positions of the members carried by the main driving shaft. Figure 34 is a face view of the mechanism for operating the platen and severing knife. Figure 35 is a face view illustrating among other features 100 the arrangement of the inking ribbon for the numbering and dating wheels, and the means by which it is operated, and the mechanism for causing proper discharge of the completed ticket. Figure 36 is a face 105 view illustrating the means for retaining the strip carrier in position and for operating the numbering wheels. Figure 37 is a face view and edge view of one of the numbering wheels, and Figure 38 is a plan view 110 of the pawl for operating the numbering wheels.

In the following description the various parts of the aforesaid figures are referred to by the letters and numerals marked thereon, 115 the same letters and numerals indicating the same or like parts in all the said figures.

The machine to be described is designed to produce tickets of four denominations or characters, rouletted for subsequent removal of a stub portion, both the body of the ticket, and the stub being numbered and dated. The main frame of the machine consists of two plates A, A' secured together by four cross bars a, a', a^2, a^3 . B is the 120 aforesaid sector shaped strip carrier which is mounted at its axis on a shaft b mounted and turned in the plates A, A'. The said strip carrier comprises a main member b' of recessed shape with the recess presented to 125 130

wards the front, and to this member there are secured an arcuate steel plate b^2 (see Figure 8) and guide members b^3 , b^4 for the strips b^5 of paper or the like. These guide members each have flanges by which they are secured to the member b' and are of two shapes, one of each kind being arranged in close juxtaposition to one of the other kind, to form a guide way between them for a strip 10 of the material. The machine illustrated is designed to deal with four different coloured strips and therefore there are four sets of the members b^3 , b^4 equi-distantly arranged and approximately radially disposed in the strip 15 carrier so that the entry ends of the guideways for the strips of material are adjacent to the axis on which the strip carrier turns. On the inner face of each member b^3 at its upper part is secured a channeled plate b^5 (see Figures 10 and 20) to constitute a precise guide for the strip. The various strips pass to the strip carrier through a slot in the base of the mechanism from rolls suitably mounted or arranged in a cabinet or case beneath the mechanism. In the 20 arcuate upper surface of the strip carrier are secured slotted steel plates b^6 , b^8 arranged coincidentally with the guideways between the guide members b^3 , b^4 respectively. The members b' , b^3 , b^4 may conveniently be made of light alloy or aluminium. In the upper part of the member b' and in the plate b^2 bearings are provided for the denominational printing rollers and 25 for the brackets carrying the impression rollers. C, C are the denominational printing rollers carried by the strip carrier, c' , c' being their bearings in the plate b^2 , and c^2 , c^3 their bearing bushes in the member b' . 30 These rollers carry provision for removably securing on them the electros and a toothed wheel for gearing with a similar toothed wheel on the impression roller, and a projecting driving shaft c^3 (see Figure 15 especially). The impression rollers D, D are 35 mounted in brackets d' , d' (see Figures 1, 13 and 14) which may turn on pins d^2 secured in the strip carrier (see Figures 1 and 6). The impression rollers D, D have 40 toothed wheels which engage with those on the printing rollers C, C so that the rollers D, D may be positively driven at the same peripheral speed as the rollers C, C as it is due to the rotation of these rolls that the 45 strip which passes between them is drawn and propelled through the machine. The said rollers D, D are covered with resilient material such as rubber and are caused to bear against the printing rollers C, C by 50 means of a threaded pin d^3 at the bottom of the bracket d' engaging in a recess d^4 in the locking member d^5 (see Figures 11 and 12) which is pivoted beneath the bracket d' on the guide member b^4 . The locking member 55 d^5 is provided with an angled edge adja-

cent to the recess d^4 so that when turned on its pivot by means of the angled finger piece d^6 (see the dotted lines in Figure 11) the pin d^3 may be disengaged from its frictional engagement in the said recess to release the pressure between the rollers C, D or so that when the member d^5 is turned inwardly the angled part d^6 is forced past the end of the said screwed pin d^3 which then engages in the said recess. The bottom 60 of the bracket d' is thus forced away from the face of the member b^4 to bring the said rollers D, C together with some pressure which is dependent upon adjustment of the pin d^3 in the bracket d' . E, E are the inking rollers which are removably mounted in brackets e' , e' beneath the printing rollers C, C, the said brackets being mounted in a vertically slidable manner on the guide members b^3 . The said rollers are caused to 65 bear against the printing rollers by means of coil springs e^2 , e^2 arranged around pins e^3 , e^3 (see Figures 9 and 10) slidably engaged in the brackets e' , e' and abutting against collars e^4 , e^4 at the lower part of 70 the said pins, which collars slidably work in bearings in brackets e^5 , e^5 secured to the members b^3 . The pins e^3 , e^3 are forced upwardly by their lower ends engaging in recesses on slides e^7 , e^7 arranged on the sides 75 of the members b^3 . Adjacent to the said recesses the said slides have angled parts e^8 which as the slides are pushed inwardly cause the pins e^3 to ride up them and enter the said recesses against the resilience of the 80 said springs e^2 . When therefore the slides e^7 are drawn outwardly, the brackets e' may be lowered, the springs e^2 passing freely through the bearings in the said brackets e^5 , in which the collars e^4 are normally situated 85 so that the rollers E, E may be removed from the machine for re-inking. For conveniently manipulating the said rollers, the outer ends of their spindles are prolonged 90 and roughened as shown in Figures 2 and 100 110 115 120 125 130

In a subsidiary frame work comprising two plates F, F' secured together, and also to the front plate A, there are mounted the numbering wheels common to the tickets of all denominations, and the dating wheels and the rollers and driving device for the inking ribbon for the said numbering and dating devices. On an adjacent subsidiary framework comprising two side plates G, G' secured together and to the front plate A, there are supported the platen for the numbering and dating devices, and severing knife and also the means for ejecting completed tickets from the machine. In order to steady the strip carrier while it is being turned, a small roller b^7 bears against its outer face (see Figure 1) which roller is carried by a bracket x which is pivoted at x' to the plate F, so that it may be turned round clear of the strip carrier when 130

replacing the inking ribbon. y is a fixed bracket under which the pivoted bracket x engages, provided with a spring stud catch at y' to prevent accidental movement of the bracket x . A plate buffer spring b^3 is provided on the base of the machine and a stop b^9 covered with rubber on its inner side is provided on the side of the plate A to form abutments to stop movement of the strip carrier in its extreme positions without shock. The members b^3 b^4 have notches b^{10} in their outer edges to admit of the strips b^5 being manipulated in their guide passages when desired.

On the rear face of the member b' of the strip carrier, there is an arcuate rib b^{11} , (see Figures 5 and 36) having four equidistant recesses b^{12} , b^{12} the positions of which correspond with the four positions of the strip carrier according to the particular strip to be dealt with. This rib is of course situated in the space between the strip carrier and the plate A and protruding through an opening in the said plate from the inner side thereof there is a roller b^{13} which may engage with any one of the said recesses b^{12} or ride over the said rib out of the said recesses when the strip carrier is being turned. The said roller is carried by an arm b^{14} pivoted on the inner face of the plate A, the said arm being resiliently held downwardly by the coil spring b^{15} connected to it, and to the said plate A. On the shaft b there is secured an arm b^{16} (see Figure 21) carrying a pin b^{17} engaging in a slot in a lever arm b^{18} secured to a shaft H mounted in bearings in the plates A, A'. On the same shaft there are also arranged the hand lever h (provided with a handle not shown) and arms h' carrying a weight h^2 counterbalancing the unbalanced weight of the strip carrier. This is best shown in Figure 21 in which however the lever h is shown in the reverse position to that shown in the other figures. When therefore the hand lever h is turned, the shaft b and strip carrier are turned against the resilient resistance of the roller b^{13} which resistance however is sufficient to cause the said roller to retain the strip carrier in any one of its four operative positions. I is the main driving shaft of the entire mechanism which is rotated by the means hereinafter described, and as it is important that while the strip carrier is being moved from one position to another it should be impossible to operate the mechanism of the machine to produce the ticket, locking devices are provided, as illustrated in Figure 21, for the said shaft while the lever handle h is being operated. These devices comprise a plate h^3 (see Figure 21) secured to the inner side of the said lever handle h having four V shaped recesses h^4 , h^4 in its upper edge, in any one of which a correspondingly shaped dog h^5 on an arm h^6 may engage. The said arm is pivoted at h^7 in a bracket secured to a plate secured to the cross bar a , and at its outer end the said arm has pivoted to it a dependent link h^8 between the lower part of which and a stud on the inner face of the plate A there is arranged a coil tension spring h^9 which tends to keep the said link in its lowermost position. The link h^8 has a slot to enable it to embrace the main shaft I with a working fit, and on its inner face has a projecting dog h^{10} adapted to engage in a slot h^{11} in a disc h^{12} secured on the said shaft. The result of this arrangement is that as the lever handle h is operated, the dog h^5 rides out of any one of the recesses h^4 with which it may have been engaged, so lifting the arm h^6 and causing the dog h^{10} to enter the slot h^{11} . Rotation of the shaft I is therefore prevented unless the said dog h^5 is properly seated in any one of the said recesses h^4 , which recesses are designed and arranged to correspond with the four depressions b^{12} and consequently the four positions of the strip carrier, in any one of which the mechanism may be operated to deal with a strip of material.

The hand operated devices for driving the mechanism for dealing with the strips of material are best illustrated in Figure 23. They comprise a hand lever i (provided with a handle not shown) extending toward the rear of the machine and secured to a shaft i' projecting through plate A', which shaft is arranged to turn in bearings in the plates A, A' and a complete oscillation or backward and forward movement of the said lever handle is arranged to impart a complete rotation to the driving shaft I by a double rack arrangement of a kind already known in connection with machines of the general class to which the present invention relates. i^2 is the double toothed rack which engages with a pinion i^3 on the shaft I on the one side, while the lever handle i is being moved in one direction, and on the other side when the said lever handle is being moved in the other direction. The rack i^2 is reciprocated through the medium of a crank i^4 and a connecting rod i^5 pivoted to the outer end thereof and to a pin i^6 on the rack. The rack i^2 is guided in its vertical movement and tilted laterally at the end of its stroke by means of a pin i^7 on the plate A' engaging in a slot i^8 in a depending member i^9 secured to the said rack, and a helical tension spring i^{10} connected to the said depending member and to the said plate in such a manner that as the rack moves vertically from one extreme position to the other, the connection of the said spring to the member i^9 is first above the pin i^7 and then below it, the result being that the said spring tends to

cause the rack to tilt laterally around the said pin according to the position of the point of connection of the spring i^{10} to the member i^9 relatively to the pin i^7 . In order that this tilting action shall only take place at the end of a stroke of the rack, a stud i^{11} is provided on the rack to co-act with the fixed rib i^{12} on the plate A', so that as the rack moves downwardly, the said stud 5 slides along the left hand side of the rib i^{12} and when the rack is in its lowermost position, the said stud is clear of the said rib thus permitting the rack i^2 to tilt to engage that side of it with the pinion φ which in its 10 downward movement was clear of the said pinion, and as the lever handle i is reversed in motion, the rack rises and the stud i^{11} immediately engages against the other side of the rib i^{12} and slides upwardly along it, so retaining the rack in gear until at the 15 top of its stroke when the said stud is again clear of the rack, and the spring i^{10} tilts the rack to the left ready for its next operation by the lever handle. Between the crank i^4 20 and a fixed stud on the plate A' the coil tension spring i^{13} is arranged which tends to keep the lever handle i in the position illustrated in Figure 23. Consequently the first half of the movement of the said lever handle is effected against the resilience of the spring i^{13} and the second half of the said movement is helped by it. This arrangement is provided for, as more power is 25 needed during the second half movement of the lever handle than during the first half of its movement. To limit the movement of the lever handle i to the proper extreme positions in each direction, a fixed abutment i^{14} is provided on the plate A' co-acting 30 with abutments i^{15} near to and carried by, an axial part on the crank i^4 . The locking mechanism hereinbefore described and illustrated in Figure 21 will prevent the strip carrier being changed in position during 35 operation of the lever handle i because the dog h^{10} on the link h^8 cannot rise into the slot h^{11} as necessary on operation of the lever handle h except in the one stationary position of the shaft I. In addition to this 40 provision, it is also important that the lever handle i for driving the mechanism cannot be reversed in movement until at the end of its first stroke in the one direction, and to provide for this, a ratchet i^{16} (see Figure 45 24) is provided on the shaft I with which engages a pawl i^{17} pivoted in a bracket secured to the cross bar a' and resiliently kept in proper engagement with the said ratchet by a coil tension spring. This pawl and 50 ratchet arrangement prevents the shaft I being rotated except in the one direction as indicated by the arrow in Figure 24 and consequently, it is impossible to reverse the proper motion for the time being of the 55 lever handle i at any time during its oscil- 60

lation, because although the oscillation consists in a stroke in one direction, and a stroke in the reverse direction, both strokes by means of the double rack arrangement produce one complete rotation of the driving shaft I in the one direction. As the strip carrier is selectively movable or adjustable in order that any one of its four sets of denominational printing mechanism may be operated, and the mechanism with- 70 in the main part of the machine for driving the said denominational printing mechanism has a fixed position in relation to the point where the ticket strip is operated on, it is necessary to provide driving and clutch 75 connections between the driving mechanism and the denominational printing mechanism, whereby the denominational printing roll in position for operation is conveniently rotated to a sufficient extent to print all the 80 required denominational matter on the strip, and is then released so that if desired the strip carrier may be moved into another position. Conveniently the denominational printing rollers are rotated one 85 complete rotation for the production of one ticket. This denominational printing roller driving mechanism will now be described. On the driving shaft I there is secured a disc c^4 (see Figure 24) partially toothed at 90 c^6 and on a stud secured to the plate A' there are mounted to rotate two toothed wheels c^6 , c^7 secured together. The toothed wheel c^6 has a part c^8 which acts as a Geneva stop in conjunction with recesses at the ends of 95 the toothed part c^6 and the periphery of the disc c^4 in a manner which will be well understood, so that the said toothed wheel c^6 is rotated by the teeth c^5 when during rotation of the shaft I they come into proper 100 position for that purpose, while at other times the toothed wheels c^6 , c^7 are prevented from rotating. The toothed wheel c^7 gears with the toothed wheel c^9 secured on a shaft 105 c^{10} turning in a bearing in the plate A' and in a bracket c^{11} secured thereto. This shaft is illustrated in Figures 25 and 26 from 110 which it will be observed that it is slotted at its front end and in the slot is engaged a clutch member c^{12} having a projecting 115 tongue also on its outer end which is designed to engage with the slot provided at the inner end of the shaft c^3 of each denominational printing roller C. The clutch member c^{12} is moved backwardly and forwardly so that it may be engaged with a denominational printing roller at one rotation of shaft I and disengaged therefrom immediately that rotation is complete by 120 means of a clutch sleeve c^{13} on the shaft c^{10} having on it a grooved collar c^{14} in the groove of which two rollers on a laterally movable fork c^{15} engage. This fork c^{15} is in 125 the form of a bell crank lever arranged to turn on a pin c^{16} secured on the lower side 130

of the cross bar a , the shorter arm of the bell crank lever being pivoted to an operating rod c^{17} carrying a roller engaging in a cam groove in a disc c^{18} secured to the shaft I. The said rod adjacent to the said disc is so shaped as to embrace the boss of the said disc with a working fit so as to guide the said rod in a horizontal direction, and prevent the cam groove and roller giving it any other movement. The clutch sleeve c^{13} is connected to the clutch member c^{12} by means of a cross pin c^{19} so that as the said clutch sleeve is moved towards the front of the machine, the clutch member moves with it. The result of the arrangement described is that as the driving shaft I commences to rotate the cam groove in the disc c^{18} operates the rod c^{17} to turn the fork c^{15} and so move the clutch member c^{12} into driving connection with that denominational printing roller carried by the strip carrier which is coincident at that time with the axis of the shaft c^{10} and by the time this engagement has been effected, the teeth c^8 operate to rotate the wheels c^6 , c^7 and drive the wheel c^9 to rotate the shaft c^{10} and clutch member c^{12} one rotation. By the time this has been done, the teeth c^8 will have passed out of operation, and the shaft c^{10} will become stationary and near the end of the rotation of the driving shaft I, the cam groove in the disc c^{18} will operate to turn the fork c^{15} towards the rear of the machine so withdrawing the clutch member from the denominational printing roller. It is important that the denominational printing rollers when out of operation, shall always be held positively in the proper position for re-engagement to prevent any accidental turning movement being imparted to them. This is effected by spring pawls c^{20} (one of which is illustrated in Figures 5 and 18) engaging with the slots in the ends c^9 of the rollers C, C respectively. The shape of the engaging parts of the said pawls are such that they are automatically depressed out of holding position on advance of the clutch sleeve c^{13} , and for this purpose they have an angled part c^{21} (see Figure 18) against which the rounded end of the said sleeve abuts in its advance, to move the pawl downwardly.

J (Fig. 30) is the rouletting wheel which is carried by the outer end of a reciprocating rod j and the mechanism by which it is operated is best illustrated in Figures 29 and 33. This mechanism comprises a cam groove in a disc j' secured to the shaft I in which cam groove there engages a roller carried by a member j^2 , which is pivoted to a bell crank lever j^3 pivoted on a plate secured to the cross bar a . The outer end of said bell crank j^3 has an arcuate rack meshing with a pinion j^4 secured to a spindle j^5 fitted in a bearing dependent from the outer side of the said plate. At its lower part the said spindle carries a toothed sector j^6 gearing with a toothed rack on the slide j^7 . The said slide is secured so that it may be reciprocated along the side of the cross bar a and carries at its lower part a boss in which the rouletting wheel carrier is secured. The member j^2 is of curved shape beneath and about its roller so as to embrace with a working fit a boss on the disc j' , in order that the said member may be guided and restrained to horizontal movement only. On examining the cam groove in the disc j' it will be observed from its form that the rouletting wheel is reciprocated comparatively rapidly just at one part of the rotation of the said disc, and that at other times the said wheel is stationary. The rouletting wheel rod j in its reciprocation passes through a suitable aperture for the purpose in the plate A, and is so arranged that it reciprocates across the platen M (Fig. 34 hereinafter described) above the ticket strip which is at that time over the said platen.

The means by which the counters for the various denominations are operated are best illustrated in Figure 22 which is a face view from the rear of the machine. K K are the respective counter devices secured on a bar k carried by the cross bars a , a' . To the edge of the said bar there is secured a dependent plate k' on which are arranged slides k^2 respectively pivoted at their upper parts to the operating cranks of the counters. At their lower parts the said slides have lateral pins k^3 arranged at equal distances from the axis of the shaft H which carries the strip carrier operating lever handle h . On that side of the said lever handle towards the front of the machine there is arranged a slide k^4 which at its upper part is provided with a laterally arranged channel k^5 in which any one of the pins k^3 may engage with a working fit as the lever handle h is turned on its axis. At its lower part the said slide k^4 is provided with a channel k^6 which is concentric with the axis of the shaft H and in this channel there engages with a working fit a pin k^7 on a member k^8 . This member is shaped to embrace the shaft H with a working fit so that it shall be guided and restrained in and to an upward movement which is imparted to it by a crank k^9 secured to the shaft i' and pivoted to the lower part of the said member k^8 . On the said shaft i' there is secured the lever handle i which operates the mechanism to deal with the ticket strip, and the result of the arrangement is that as that lever handle is moved, the member k^8 and slide k^4 are raised, thereby pushing upwardly that one of the slides k^2 of which the pin k^3 is engaged with the said slide k^4 , so operating the crank of the counter to which the particular slide k^2 is connected.

and as the lever handle i is given its return stroke, the parts are caused to resume their normal position. It will be appreciated that the operative parts immediately connected with each counter are automatically caused to associate with the mechanism by which they are operated, as the lever handle h is brought into one or other of its four positions corresponding to the four ticket strips accommodated in the machine and the mechanism carried by the lever handle h is so designed that it is operated in exactly the same way irrespectively of the position of the said lever handle h .

The numbering and dating mechanism for the tickets is common to all the strips and is carried by the plates F F' which are secured together by distance bars or rods and to the plate A , but a short distance therefrom, as will be seen from Figure 2. All the numbering and dating wheels are arranged around the same axis or spindle f . f^1 are four numbering wheels, and f^2 are wheels for dating with the month and the day of the month. Each numbering wheel has secured to it a ratchet wheel f^3 (see Figures 36 and 37) with teeth spaced to correspond with the spacing of the numbers on the wheel and the said numbering wheels are operated by a spring pawl f^4 (see Figures 36 and 38) which engages with the said teeth, and is carried by a member f^5 pivoted around the spindle f . This member f^5 is reciprocated to cause the pawl f^4 to turn the numbering wheels tooth by tooth for each operation of the printing mechanism by means of a connecting rod f^6 pivoted to the member f^5 , some distance from the axis on which it turns, and at its lower part pivoted to the front side of the upper part of the member k^8 (see Figures 35 and 36). As before pointed out, this member k^8 makes a complete vertical reciprocation for each operation of the mechanism. The connecting rod f^6 is arranged between the plates A and F and operates the member f^5 through a slot in the plate F . A pawl f^7 is arranged in connection with the ratchet of each numbering wheel to restrain it from movement except when being positively operated, the said pawls being raised by the ratchet teeth against the action of small coil springs f^8 arranged between the said pawls and a cross bar f^{10} , between the plates F F' (see Figures 2 and 36). Somewhat similar spring pawls are provided in connection with the dating wheels, each of which wheels has fixed to it a scalloped disc f^{11} with which the said spring pawls engage (see Figure 35). The dating wheels are adjusted by hand by turning milled discs f^{12} arranged at the outer ends of their respective bushes. The unit numbering wheel is actuated by each operation of the mechanism and the tens, hundreds and

thousands wheels are operated at the proper times by known devices. For this purpose the ratchet f^3 of each numbering wheel except the thousands wheel has a depression f^{13} (see Figure 37) and the four teeth of the pawl f^4 are all varying in depth as will be well understood.

In order that all the numbering wheels may be brought to zero when desired, each is provided with a spring pawl f^{14} (see Figure 37) as usual, all the said pawls being designed to engage with an axial groove in the spindle f which at its outer end is provided with a milled operating knob f^{15} . All numbers and characters on the numbering and dating wheels are in duplicate along the periphery of each wheel so that at each operation duplicate numbering and dating characters are presented to the platen M and print the matter in duplicate on the strip in such position and at such distance apart that the rouletting takes place across that part of the ticket between them leaving one numbering and dating on the body of the ticket quite clear of the rouletting and the other similarly on the stub part. The numbering and dating for both the ticket and stub are therefore on the same side of the strip and it is not possible by accident to alter the numbering and dating for the ticket apart from that for the stub. The inking for the numbering and dating wheels is effected by an endless tape or ribbon L (not shown in Figure 2 but see Figure 35) which passes around rollers mounted on the bars l l by which the plates F F' are secured together and also around a roller l' covered with felt or the like. The said inking ribbon is kept taut by means of a jockey roller l^2 carried by an arm l^3 pivoted to turn on a stud carried by the plate F' . The inking ribbon L is moved forwardly on each operation of the mechanism by means of the ratchet l^4 on the shaft of the roller l' with which engages a spring pawl l^5 , pivoted to the stud on the member k^8 , to which the connecting rod f^6 is pivoted, another pawl l^6 being provided to prevent reverse movement of the roller l' . The platen M and ticket severing knife N (see Figures 1 and 34) are carried by two plates m^1 secured together and pivoted at m^2 in a swinging bracket comprising arms m^3 arranged to turn at their upper parts on the cross bar m^4 between the plates G G' . The bracket m^1 is operated to bring the platen M forward and so press the ticket strip against the inking ribbon and numbering and dating wheels and the severing knife N into action by mechanism which is best shown in Figures 33 and 34. The spindle m^2 by which the plates m^1 are pivoted to the bracket m^3 is extended rearwardly through an aperture in the plate A , and at its rear end has a working fit in a slot at the upper part of a

lever m^5 which is pivoted at bottom to the bracket secured to the cross bar a' . The said lever arm has secured to it a dog o^5 , and the disc j' is provided with a peripheral cam o^6 which during the course of rotation of the driving shaft I engages under the 70 said dog, and lifts the lever arm o^4 , so causing the cup shaped arm O to be turned down and press the ticket strip on the platen M. The weight of the arm o^4 causes its return to normal position. 75

As the said rod m^6 is reciprocated by the cam groove in the disc m^7 and roller aforesaid, so the plates m' carrying the platen M and severing knife N are swung to and fro. The said platen is of rubber or similar suitable resilient material. In order that the platen and severing knife may have a defined and guided movement there is provided a roller m^8 on a stud on the side 20 of the inner plate m' which engages in a groove m^9 of suitable shape (see Figure 34) in a block secured to the plate A. This device guides the plates m' in their movement. Just when the final pressure is being 25 put on the strip by the platen the knife cuts the said strip adjacently to the side of the slot in the steel plate b^6 . In Figure 34 lines shown at 1, 2, 3, and 4 indicate certain parts of the cam groove in the disc 30 m^7 at which during its rotation occur certain actions of the rouletting wheel and the parts actuated by the cam illustrated in the said figure, as now described. When the part 1 of the cam reaches the roller in 35 the said cam groove the rouletting stroke is commencing, and when the part 2 arrives in this position the rouletting stroke is ended and the platen and severing knife are then moved a slight distance back from 40 their normal position. At the point 3 the end of the return stroke of the rouletting wheel occurs and at the point 4 there begins the forward stroke of the platen and severing knife. 45

While the rouletting stroke is taking place, a device is provided for holding the ticket strip against the platen M and the device provided for this purpose will now be described. It comprises an arm O (see 50 Figure 31) having a cup shaped extremity which when the said arm is turned, may bear on the ticket strip leaving a recess constituting a passage for the rouletting wheel. The said arms is pivoted on one of 55 the cross bars by which the plates G G' are secured together, and has a slotted tail with which engages a pin o on an arm secured to a spindle o' turning in bearings in the plates G G' and passing to the rear through 60 the plate A (see Figure 25). At the rear extremity of this spindle there is secured a lever arm o^2 to which is pivoted the lower end of the connecting rod o^3 the upper end of which is pivoted to the lever arm o^4 , 65 which at its other end is pivoted in a

In order that the ticket strip may be properly guided at its upper end, a thin steel plate P (see Figure 35) is provided between the plates G G' and secured to the uppermost bar by which those plates are secured together. 80

It is necessary that the severed ticket should be properly ejected clear of the machine, and this is effected by the mechanism which will now be described. Mounted on 85 a spindle turning in bearings in the plates G G' is a serrated sector R (see Figure 35) which co-acts at the proper time with a serrated roller r spring mounted on the plate r' which is secured to the plate F'. The said roller is disposed in a slot in the said plate r' and when the sector R is in operation, the said sector works through a slot in the steel plate P. The spindle of the sector R is prolonged to the rear through 90 the plate A and is there provided with the toothed pinion r^2 which gears with a rack on a member r^3 pivoted at its lower part to a lever r^4 pivoted to the plate A and also connected by a pivot to the lower end of 100 a member r^5 carrying at its upper part a lateral dog or stud r^6 , which co-acts with a cam on the disc r^7 . The upper end of the member r^5 is curved to embrace the boss of the disc r^7 with a working fit, so that the 105 said member shall be restrained from lateral motion at that part. On examination of the said cam it will be observed that at the beginning of the rotation of the driving shaft I the member r^5 is quickly lifted so 110 bringing the serrated sector R into position below the serrated wheel r so as to leave a clear passage for the strip between the wheel r and segment R while the strip is being printed. The member r^5 is provided 115 with a coil spring r^8 connected at its lower end to a stud on the plate A so that when the driving shaft I is near the end of its rotation, the dog or stud r^6 is allowed to fall quite rapidly into the position shown in 120 Figure 35 whereby the sector R is moved rapidly past the wheel r into the position shown in that figure, so gripping the severed ticket and causing it to pass quickly by the other end of the thin plate P and so 125 ejecting it from the machine.

In order to insert in proper position in the machine any one of the strips of material, the corresponding impression roller is released from close contact with its 130

printing roller by turning out the pivoted locking member d^5 and the strip of material is threaded into the guide way between the guide members b^3 b^4 on the strip carrier from below, and caused to pass upwardly therein by manipulating it where the coincident notches b^{10} occur, until the upper end of the strip is about coincident with the face of the plate b^6 . The pivoted locking member d^5 is then replaced, thus tilting outwardly the tail end of the bracket d' and causing the impression roller to pinch the strip between it and the corresponding printing roller.

It is probable that the general sequence of operations in the machine will be understood from the foregoing description, but it is thought well briefly to recapitulate them here. The strip carrier is first turned into proper position by means of the hand lever h and intermediate mechanism, to bring that coloured strip into position for operation which is suitable for receiving the selected printed denomination. While this is being done, the hand lever i cannot be operated by reason of the devices illustrated in Figure 21. On the other hand by reason of the same devices, the strip carrier cannot be operated if the hand lever i is not in its initial position as illustrated. The hand lever i is now operated towards the right from the position shown in the drawings, and at the limit of that stroke is returned to its initial position. This reciprocation of the hand lever should be performed somewhat rapidly and by it the following actions are caused to take place. At the commencement of rotation of the shaft I the clutch member c^{12} is caused to move outwardly to engage the coincident denominational printing roll, and the cam on the disc r^7 acts to bring the serrated sector R into operative position. About the same time, turning of the shaft i' causes upward movement of the member k^9 so operating the slide k^4 and that one of the counters with which it is then in mechanical connection, by reason of the position of the hand lever h , which of course depends on the position of the strip carrier. This movement of the member k^8 also causes a slight travel of the inking ribbon L through the pawl and ratchet l^4 l^5 and also of the numbering wheels through the connecting rod f^6 . Meanwhile the teeth c^5 on the disc c^4 have commenced to engage the pinion c^6 , so rotating the clutch member c^{12} and this rotation continues until the hand lever i is about at the end of its first stroke. The denominational printing roller is thus given a complete rotation by about this time, and the portion of the strip from which the ticket is being produced has been driven forward over the platen M . At this moment, the cam o^6 causes the pivoted arm o^4 to rise and the

holding device O to descend rapidly on to the portion of the strip over the platen, and immediately after the cam groove in the disc j' rapidly acts through the member j^2 and toothed gear j^4 j^6 to cause the rouletting wheel J to pass transversely over the strip on the platen which is then in normal position, through the recess in the holding device. When this has taken place the platen slightly recedes (see Figure 34), and at the end of the return stroke of the rouletting wheel the platen bracket and severing knife are caused to move forwardly to press the portion of the strip lying on the platen against the numbering and dating wheels through the medium of the inking ribbon, whereby the ticket receives its numbering and dating a short distance from the rouletting on each side of it. As the platen arrives near the end of its forward stroke the severing knife N which has previously been brought into close proximity to the rear face of the strip, severs the strip in co-operation with the sharp edge of the exit slot in the steel plate b^4 . The platen and severing knife then begin to retire and the spring r^8 is acting to cause the stud r^6 to approach the shaft rather rapidly and so cause rapid upward turning action of the ejector segment R' past the wheel r until it again reaches its initial position shown in Figure 35. While this has been taking place the cam groove in the disc c^4 is acting to cause retirement of the clutch member c^{12} to its initial position also. At this time the shaft I has made a complete rotation and the hand lever i is again in its position illustrated in the drawings. A ticket has been printed with denominational printing rouletted, numbered, dated, severed and ejected from the machine.

A suitable casing is provided around the mechanism and this casing is preferably provided with locking arrangements so that it may only be removed or opened by an authorized person. The casing preferably covers the whole of the mechanism except the hand levers h i so that it, or a portion of it must be unlocked to operate the dating wheels or bring the numbering wheels to zero, to rearrange the strips in relation to the various sets of denominational printing means or to lead in a new strip. Indications should be provided adjacently to the hand lever h to indicate the character of strip which will be operated on in any one of the four positions of the said hand lever, and it is preferred that the casing should have an aperture at this part so that the counters may be observed. Adjacently above the ticket ejecting means the casing must be provided with a slot for the ticket to pass through on its way to a cup shaped or other suitable receptacle from which it may be removed by the user.

What I claim and desire to secure by Letters Patent of the United States is:—

1. A machine for printing and issuing tickets comprising a plurality of sets of devices each adapted to print distinguishing characters upon one of a plurality of ticket strips, a single set of devices adapted to imprint upon all of the strips matter common to all of the tickets to be issued, means for effecting relative movement between said single set of devices and said plurality of sets to cause said single set to receive the printed section of a strip ejected from any of said plurality of sets, and means carried by said single set of devices for severing the tickets from all of the strips.
2. A machine for printing and issuing tickets comprising means for supporting and feeding a plurality of ticket strips, and printing distinguishing characteristics upon each said strips, and a single set of devices adapted to imprint common subject matter upon all of the tickets including a single delivery passage adapted to receive the printed portion of any one of said strips.
3. In a machine of the class described, the combination of a plurality of ticket printing devices cooperating with a plurality of ticket strips, each device printing different data upon their respective strips, a single set of ticket printing devices common to all of the ticket strips, a sector shaped carrier carrying said plurality of sets of devices and being movable on its axis with its peripheral edge adjacent said single set of devices, means whereby the strips of material pass through said carrier from its axis to its periphery, means for turning said carrier at will on its axis into any one of a plurality of positions whereby any one of said plurality of devices may be positioned to operative relationship with said single set of devices, and means for feeding the positioned strip from said carrier to said single set of devices.
4. In a machine of the class described, the combination of a movable ticket strip carrier having a plurality of sets of ticket printing devices, a single set of ticket printing devices common to all of the ticket strips, means for positioning said carrier at will to bring any desired one of said first mentioned sets of devices into operative relationship with said single set of devices, spring actuated means for resiliently retaining the carrier in any one of its operable positions, and means for feeding the strip from any one of the first mentioned sets of devices to said single set of devices.
5. In a machine of the class described, the combination of a movable strip carrier adapted to have ticket strips pass therethrough, a plurality of sets of ticket printing devices on said carrier, a single set of ticket printing devices common to all of the ticket printing devices common to all of the

ticket strips, means for moving said carrier at will to any one of a plurality of positions and thereby positioning one of the first mentioned sets of devices in operative relationship to said single set of devices, means for feeding the strip from said carrier to said single set of devices whereby it is printed by said single set of devices, a separate counter for each class of tickets, operating means for each counter, and means whereby the appropriate counter is automatically connected with the operating means upon adjustment of the strip carrier to any one of its positions.

6. In a machine of the class described, the combination of a movable strip carrier adapted to have a plurality of ticket strips pass therethrough, a plurality of sets of ticket printing devices on said carrier, a single set of ticket printing devices having a passage common to any strip which is fed from said carrier, means for moving the carrier at will to any one of a plurality of positions and thereby positioning one of the said first mentioned sets of devices so that it is in operative relationship with said single set of devices, means whereby the selected strip is fed from said carrier through said passage to be printed upon by said single set of devices, and automatic locking means for preventing the operation of the ticket printing devices unless the strip carrier is in one of its predetermined positions.

7. In a machine of the class described, the combination of a movable ticket strip carrier adapted to have ticket strips passed therethrough, a plurality of sets of ticket printing devices on said carrier, a single set of ticket printing devices common to all of the ticket strips, means for moving said carrier at will to any one of a plurality of positions whereby one of the first mentioned sets of devices is moved into operative relationship with said single set of devices, means for feeding the ticket strip from said carrier after it has been printed upon by one of the first mentioned sets of devices to said single set of devices so that it may be printed thereby, and automatic locking means for preventing movement of the strip carrier during the printing or feeding of the ticket strip.

8. In a machine of the class described, the combination of a main operating mechanism, a movable strip carrier adapted to have ticket strips passed therethrough, a plurality of sets of ticket printing devices on said carrier, a single set of ticket printing devices common to all of the ticket strips, means for disposing said carrier at will in any one of a plurality of positions where one of said first mentioned sets of devices is moved into operative relationship with said single set of devices, a normally disengaged rotary and axially reciprocatory clutch

operated by the main operating mechanism to engage and operate to a predetermined extent the set of devices as positioned by said carrier.

9. In a machine of the class described, the combination of a plurality of sets of ticket printing devices including a single member having duplicate type for making two impressions upon a ticket, a single set of ticket printing devices, means for changing the relative position between said single set of devices and said plurality of sets of devices whereby said single set of devices may print upon any desired strip, and means for perforating said ticket between the two impressions thereon.

10. In a machine of the class described, the combination of a plurality of sets of ticket printing devices, each having type wheels bearing duplicate type for making two impressions upon a ticket, a single set of ticket printing devices, means for changing the relative position between said plurality of sets of devices and the single set of devices whereby said single set of devices may print upon any desired strip, numbering and date wheels adapted to number and date each ticket in two places simultaneously, and means for perforating the ticket between the two sets of printed impressions thereon.

11. In a machine of the class described, the combination of a main operating mechanism, a plurality of sets of ticket printing devices, a single set of ticket printing devices common to said plurality of sets of devices, means for changing the relative position of the plurality of sets of devices to the single set of devices whereby said single set of devices may be caused to print upon any desired ticket strip, a perforating device operated by the main operating mechanism to travel across the strip, a platen cooperating with said perforating device, and means for holding the strip against the platen during the travel of the perforating devices.

12. A machine for printing and issuing tickets comprising a carrier provided with a plurality of channels each adapted to receive a ticket strip and means cooperating with each channel for feeding a strip therethrough and imprinting distinguishing characters upon said strip, a delivery carrier provided with a passage for a ticket strip and with means for imprinting on a strip in said passage matter common to all of the tickets to be issued, means for effecting relative movement between said carriers to align the passage in the delivery carrier with any selected channel of the first said carrier, and means for severing the completed ticket from a strip.

13. A machine for printing and issuing tickets comprising a pivotally mounted, sec-

tor shaped, carrier provided with a plurality of channels that diverge from adjacent the axis of the carrier, means adjacent the outer end of each channel for feeding a strip through the channel and imprinting distinguishing characters thereon, a delivery carrier provided with a passage adapted to receive any of the ticket strips and with means for imprinting on the strip therein matter common to all of the tickets, means for rocking the first said carrier to position any selected channel thereof in alignment with the passage in the delivery carrier, and means for severing the printed ticket from a strip.

14. A machine for printing and issuing tickets comprising a relatively flat, pivotally mounted, sector shaped plate provided on one face with ribs forming a plurality of channels diverging from the axis of said plate and each adapted to receive a ticket strip, printing and feed rolls mounted on said plate adjacent the outer end of each channel for feeding a strip and imprinting thereon distinguishing characters, means beyond the outer end of said plate for imprinting matter common to all of the tickets, means for turning the strip carrying plate to bring any selected channel thereof into position to cause the strip therein to be fed into the path of the last said printing means, and means for severing the printed ticket from its strip.

15. A machine for printing and issuing tickets comprising a relatively flat, pivotally mounted, sector shaped plate provided on one face with ribs forming a plurality of channels diverging from the axis of said plate and each adapted to receive a ticket strip, means for feeding a strip through each said channel, printing means adapted to imprint distinguishing characters upon the strip in each channel, means arranged beyond the outer end of the strip carrying plate for imprinting matter common to all of the tickets, means for rocking the strip carrying plate to bring any one of the channels therein into operative relation to the common printing means, and a single knife adapted to sever completely printed tickets from all of the strips.

16. A machine for printing and issuing tickets comprising a carrier provided with a plurality of channels each adapted to receive a ticket strip, means for feeding a strip through each said channel, a printing roller adapted to imprint distinguishing characters upon the strip in each channel, means normally preventing actuation of said printing rollers, means arranged beyond the outer end of the strip carrier for imprinting matter common to all of the tickets, means for positioning said common printing means in operative relation to any selected one of the carrier channels, and means for releasing the printing roller of the channel.

that is in operative relation to the common printing means.

17. In a machine of the class described, the combination of a plurality of adjustable strip feeding devices, printing mechanism common to all of said devices, and means for adjusting all of said devices to bring any desired one into operative relation with said printing mechanism.
- 10 18. In a machine of the class described, the combination of a plurality of adjustable strip feeding devices, printing mechanism common to all of said devices, and manipulative means for adjusting all of said devices 15 to bring any desired one into operative relation with said printing mechanism.

19. In a machine of the class described, the combination of a plurality of adjustable strip feeding devices, printing mechanism common to all of said devices, and means operable as a preliminary to an operation of the machine for adjusting all of said devices to bring any desired one into operative relation with said printing mechanism.

- 25 20. In a machine of the class described, the combination of a plurality of feeding devices, a differentially adjustable support for said devices, printing mechanism common to all of said devices, and means for 40 adjusting said support to bring any desired feeding device into operative relation with said printing mechanism.

21. In a machine of the class described, the combination of a plurality of feeding devices, a differentially adjustable support for said devices, printing mechanism common to all of said devices, means for adjusting said support to bring any desired feeding device into operative relation with 45 said printing mechanism, and means for retaining said support in its adjusted position.

22. In a machine of the class described, the combination of a plurality of feeding devices, a differentially adjustable support 45 for said devices, printing mechanism common to all of said devices, means for adjusting said support to bring any desired feeding device into operative relation with the printing mechanism, and means for locking the printing mechanism during the adjustment of said support.

23. In a machine of the class described, the combination of a plurality of adjustable strip feeding devices, normally disengaged driving means common to all of the devices, printing mechanism common to all of the devices, means operable as a preliminary to an operation of the machine for adjusting said devices to bring any desired one 55 into operative relation with said printing mechanism, and means for engaging said driving means with the positioned device.

24. In a machine of the class described, the combination of a plurality of adjustable strip feeding devices, normally dis-

engaged driving means common to all of the devices, means operable as a preliminary to an operation of the machine for adjusting said devices to bring any desired one into operative relation with the driving means, 70 and means for engaging said driving means with the positioned device.

25. In a machine of the class described, the combination of a plurality of adjustable strip feeding devices, normally disengaged 75 driving means common to all of the devices, severing means common to all of the strips, means operable as a preliminary to an operation of the machine for adjusting said devices to bring any desired one into operative 80 relation with the driving means, means for engaging said driving means with the positioned device, and means for operating the severing means to sever the selected strip.

26. In a machine of the class described, 85 the combination of a plurality of adjustable strip feeding devices, severing means common to all strips, means operable as a preliminary to an operation of the machine for adjusting said devices to bring any desired one into operative relation with the severing means, and means for operating the severing means to sever the selected strip.

27. In a machine of the class described, 95 the combination of a plurality of adjustable ticket printing devices, a single printing device common to the first mentioned devices, and means operable as a preliminary to an operation of the machine for adjusting all 100 of the plurality of devices to bring any desired one into operative relation with said single device.

28. In a machine of the class described, the combination of a plurality of adjustable ticket printing devices, each device adapted 105 to print its respective data on a corresponding strip, a single printing device common to the first mentioned devices and adapted to print common data on all strips, manipulative means for adjusting said plurality of 110 devices to bring any desired strip into operative relation with said single device, means for severing the printed ticket from the strip, and means for feeding the severed ticket from the machine.

- 115 29. In a machine of the class described, the combination of a main operating mechanism, a plurality of adjustable ticket printing devices, a single printing device common to the first mentioned devices, and means 120 operable as a preliminary to an operation of the main operating mechanism for adjusting all of the plurality of devices to bring any desired one into operative relation with said single device.

30. In a machine of the class described, the combination of a main operating mechanism, a plurality of adjustable ticket printing devices, a single printing device common to the first mentioned devices, means oper- 130

- able as a preliminary to an operation of the main operating mechanism for adjusting all of the plurality of devices to bring any desired one into operative relation with said 5 single device, and means for preventing an operation of the main operating mechanism during the adjusting of said plurality of devices.
31. In a machine of the class described, 10 the combination of a main operating mechanism, a plurality of adjustable ticket printing devices, a single printing device common to the first mentioned devices, means operable as a preliminary to an operation of the 15 main operating mechanism for adjusting all of the plurality of devices to bring any desired one into operative relation with said single device, and a device for locking the adjustable devices in position during an 20 operation of the main operating mechanism.
32. In a machine of the class described, 25 the combination of a main operating mechanism, a plurality of adjustable ticket printing devices, a single printing device common to the first mentioned devices, means operable as a preliminary to an operation of the main operating mechanism for adjusting all of the plurality of devices to bring any desired one into operative relation with said 30 single device, and means for resiliently retaining the adjustable devices after the adjustment until the main operating mechanism is operated.
33. In a machine of the class described, 35 the combination of a plurality of adjustable ticket printing devices each device adapted to print its respective data on the corresponding strip, a single printing device common to the first mentioned devices and adapted to print common data in duplicate on all strips, manipulative means for adjusting said plurality of devices to bring any desired strip into operative relation with said single device, and means for perforating the 40 strip between the duplicate impressions thereon.
34. In a machine of the class described, 45 the combination of a plurality of adjustable ticket printing devices each adapted to print its respective data on the corresponding strip, a single printing device common to the first mentioned devices and adapted to print common data in duplicate on all strips, manipulative means for adjusting said plurality of devices to bring any desired strip into operative relation with said single device, and means adapted to receive an excursion across the strip to perforate the same.
35. In a machine of the class described, 50 the combination of a plurality of adjustable ticket printing devices each adapted to print its respective data on the corresponding strip, a single printing device common to the first mentioned devices and adapted to print common data in duplicate on all strips, manipulative means for adjusting said plurality of devices to bring any desired strip into operative relation with said single device, and means adapted to receive an excursion across the strip to perforate the same.
36. In a machine of the class described, 55 the combination of a plurality of adjustable ticket printing devices each adapted to print its respective data on the corresponding strip, a single printing device common to the first mentioned devices and adapted to print common data in duplicate on all strips, manipulative means for adjusting said plurality of devices to bring any desired strip into operative relation with said single device, a serrated roller, and means for giving said roller an excursion across the strip to perforate the 60 same.
37. In a machine of the class described, 65 the combination of a plurality of adjustable ticket printing devices each device adapted to print its respective data on a corresponding strip, a single printing device common to the first mentioned devices and adapted to print common data in duplicate on all strips, means for perforating the strip between the 70 duplicate impressions thereon, and means for holding the strip while it is being perforated.
38. In a machine of the class described, 75 the combination of a plurality of adjustable ticket printing devices each adapted to print its respective data on the corresponding strip, a single printing device common to the first mentioned devices and adapted to print common data in duplicate on all strips, means for perforating the strip between the 80 duplicate impressions thereon, means for holding the strip while it is being perforated, means for severing the printed ticket from the strip, and means for feeding the severed ticket from the machine.
39. In a machine of the class described, 85 the combination of a plurality of adjustable ticket printing devices, a set of type wheels common to said devices, a main operating mechanism, means operable as a preliminary 90 to an operation of the main operating mechanism for adjusting said plurality of devices to bring any desired one into operative relation with the type wheels, and a platen operated by the main operating mechanism for 95 taking an impression on the ticket strip from the said type wheels.
40. In a machine of the class described, 100 the combination of a plurality of adjustable ticket printing devices, a set of type wheels 105 common to said devices, a main operating mechanism, means operable as a preliminary to an operation of the main operating mechanism for adjusting said devices to bring any desired one into operative relation with 110

- the type wheels, a platen operated by the main operating mechanism for taking an impression on a ticket strip from the said type wheels, and severing means operated simultaneously with the platen for severing the printed ticket from the strip.
41. In a machine of the class described, the combination of a plurality of adjustable ticket printing devices, a set of type wheels common to said devices, a main operating mechanism, means operable as a preliminary to an operation of the main operating mechanism for adjusting said devices to bring any desired one into operative relation with the type wheels, a platen, means for severing the printed ticket from the strip, and means operated by the main operating mechanism for simultaneously operating the platen and the severing means.
42. In a machine of the class described, the combination of a plurality of adjustable ticket printing and feeding devices, means common to all devices for severing the printed tickets from the strips, and means operable as a preliminary to an operation of the machine for adjusting said devices to bring any desired one into operative relation with the severing means.
43. In a machine of the class described, the combination of a plurality of adjustable ticket printing and feeding devices, means common to all devices for severing the printed tickets from the strips, means operable as a preliminary to an operation of the machine for adjusting said devices to bring any desired one into operative relation with the severing means, and means for feeding the severed ticket from the machine.
44. In a machine of the class described, the combination of a plurality of adjustable ticket printing and feeding devices, means common to all devices for severing the printed tickets from the strips, a differentially adjustable support for said devices, and means operable as a preliminary to an operation of the machine for differentially adjusting said support to bring any device into operative relation with said severing means.
45. In a machine of the class described, the combination of a main operating mechanism, a plurality of adjustable ticket printing and feeding devices, means common to all devices for severing the printed tickets from the strips and operated by the main operating mechanism, manually operated means for adjusting said devices to bring any desired one into operative relation with the severing means and means operated by the main operating mechanism for feeding the severed ticket from the machine.
46. In a machine of the class described, the combination of a plurality of adjustable ticket printing and feeding devices, a ticket strip guide for each device, an adjustable support common to and supporting all
- guides, a guide common to all strips and adapted to receive them as they are fed from their respective devices, and means operable as a preliminary to an operation of the machine for adjusting said support to bring the desired guide into operative relation with said common guide.
47. In a machine of the class described, the combination of a plurality of adjustable ticket printing and feeding devices, a ticket strip guide for each device, an adjustable support common to and supporting all guides, a guide common to all strips and adapted to receive them as they are fed from their respective devices, means operable as a preliminary to an operation of the machine for adjusting said support to bring any desired guide into operative relation with said common guide, and means for severing the ticket from the strip after it has entered said common guide.
48. In a machine of the class described, the combination of a plurality of adjustable ticket printing and feeding devices, means common to all devices for severing the printed tickets from the strips, a plurality of counters one for each device, an adjustable counter operating device common to all counters, and means operable as a preliminary to an operation of the machine for adjusting the ticket devices to bring any desired one into operative relation with the severing means and for adjusting the counter operating device to position it to operate the counter corresponding to the positioned ticket device.
49. In a machine of the class described, the combination of a plurality of adjustable ticket printing and feeding devices, means common to all devices for severing the printed tickets from the strips, a plurality of counters one for each device, an adjustable counter operating device common to all counters, and means operable as a preliminary to an operation of the machine for adjusting the ticket devices to bring any desired one into operative relation with the severing means and for simultaneously adjusting the counter operating device to position it to operate the counter corresponding to the positioned ticket device.
50. In a machine of the class described, the combination of a plurality of adjustable ticket printing and feeding devices, means common to all devices for severing the printed tickets from the strips, a plurality of counters one for each device, a counter operating device common to all counters, and means operable as a preliminary to an operation of the machine for adjusting the ticket devices to bring any desired one into operative relation with the severing mechanism and for simultaneously selecting the respective counter for operation.

FREDERICK PHILLIPS.
